UNITED STATES PATENT OFFICE.

HERMAN A. POPPENHUSEN, OF CHICAGO, AND JOSEPH HARRINGTON, OF RIVERSIDE,
ILLINOIS.

ROTARY PUMP OR MOTOR.

No. 918,906.

Specification of Letters Patent. Patented April 20, 1909.

Application filed November 11, 1908. Serial No. 462,072.

To all whom it may concern:

Be it known that we, HERMAN A. POPPENHUSEN and JOSEPH HARRINGTON, citizens of the United States, and residents of Chicago and Riverside, respectively, in the county of Cook and State of Illinois, have invented certain new and useful Improvements in Rotary Pumps or Motors; and we do hereby declare that the following is a full, clear, and exact 10 description thereof, reference being had to the accompanying drawings, and to the numerals of reference marked thereon, which form a part of this specification.

This invention relates to improvements in 15 rotary pumps or motors of that type having a cylindric casing and a rotary piston eccentrically mounted in said casing and having contact at one side with the interior cylindric surface of the casing combined with radially 20 movable abutments which bear at their inner ends against the rotative piston and which slide in slots in the cylinder wall; said abutments serving to divide the interior of the casing into a plurality of chambers each of 25 which is alternately enlarged and lessened in interior capacity in the rotative movement of the eccentric piston.

The invention relates more specifically to 30 valve mechanism for controlling the admission of fluid to the pump cylinder and embraces also other features of improvements in apparatus of this type which will herein-after more fully appear.

The improvements constituting our invention 35 are more particularly applicable to pumps or compressors employed for compressing air or gases, and the apparatus illustrated in the accompanying drawings is designed for use as such a compressor.

As shown in the drawings:—Figure 1 is a 40 partial side elevation and partial vertical section of a pump or compressor made in accordance with our invention. Fig. 2 is a transverse section thereof, the sections of the 45 several parts being taken in different transverse planes. Fig. 3 is a detail section taken on the line 3—3 of Fig. 1. Fig. 4 is an end view of the rotating piston, showing one end wall and flange, which latter is arranged to 50 constitute part of the inlet valve mechanism. Fig. 5 is an inner face view of one of the cylinder heads. Fig. 6 is a section taken on line 6—6 of Fig. 2.

As shown in the drawings, 10 designates a 55 horizontally arranged casing or pump cylin-

der which is supported on legs or standards 11, 11.

12, 12 designate the end plates or heads of the cylinder which are fastened to flanges 13 of the cylinder by bolts 14. For convenience 60 of manufacture, the cylinder is made of upper and lower parts joined on a horizontal plane, as clearly shown in Fig. 2; the connection of the ends or heads 12 with the two parts of the cylinder serving to rigidly unite 65 the two cylinder members.

15 designates a rotary piston within the cylinder. Said piston is of cylindric form and is affixed eccentrically to a horizontal shaft 16, that extends outwardly through the 70 cylinder heads and has bearing in elongated bearings or hubs 17 on said heads. Said shaft is rotatively mounted at its ends in bearings supported by standards 18, 18. The shaft is provided at one end with a drive 75 wheel or pulley 19 and at its other end with a fly wheel 20, the said wheel and pulley being located inside the standards 18, 18. The eccentric arrangement of the rotative piston 15 within the cylinder gives contact of the part 80 of the piston having greatest eccentricity with the inner surface of the cylinder wall, along a line parallel with the axis of the cylinder and the piston is provided with any suitable packing means, as the longitudinal 85 packing strips 21, adjacent to and parallel with said line of contact, to afford an air tight joint between the piston and cylinder along this line.

22, 22 designate radially arranged sliding 90 abutments which bear at their inner ends with an air tight fit against the cylindric surface of the rotative piston, throughout the length of the latter. The said sliding abutments 22 extend outwardly through 95 longitudinal slots in the cylinder wall, in which slots they radially slide. As shown in the accompanying drawings, the slots in which said abutments slide are formed between the upper and lower members or 100 halves of the cylinder, and the cylinder wall is provided above and below the slots with longitudinal packing strips 23, which bear upon the upper and lower faces of the abutments to provide air and gas tight joints between said parts and thereby prevent the 105 escape of air or gas from one chamber or compartment of the cylinder to another. The upper and lower members of the cylinder shell are provided at the ends thereof 110

2

with upper and lower lugs 24, 24 as most clearly shown in Figs. 1, 2 and 3, which constitute elongated guides for the sliding abutments and increase the area of the bearing 5 between said abutments and the cylinder structure. Said lugs are joined outside of the ends of the abutments by bolts 25 which constitute additional means for fastening the two parts or members of the cylinder 10 together. The said abutments 22 divide the cylinder into two separate compressing chambers, as common in pumps or compressors of this type, each space serving alternately as a compressing chamber and an inlet 15 chamber. Each end wall of the cylinder is provided with two inlet ports 29, 29, the two ports in each end wall or head being located adjacent to one of the abutments, and one being located above and the other 20 below its associated abutment. Each chamber or compartment of the cylinder thus formed is provided with an exit or delivery port 30, located each adjacent to one of the abutments, one of the exit ports being located 25 at one side of its associated abutment and the other at the opposite side of its associated abutment. The said exit ports are controlled by spring actuated back-pressure valves, designated as a whole by 31, which 30 may be of any preferred type, and the compressed air or gas delivered from the pump is carried away through pipes 32, 32 connected with the cylinder by said back pressure valves. The rotating piston is provided at its ends 35 with circular flanges 35, 35 the margins of which are concentric with the axis of the cylinder and therefore eccentric to the rotating piston. The said flanges 35 fit or bear against the inner faces of the heads 12, 12 of 40 the cylinder, as shown in Figs. 1, 3 and 6, and the end margins of the sliding abutments fit or bear against the inner faces of said flanges. Each of said piston flanges is provided for a distance around its peripheral 45 margin with a plurality of radially arranged ports 37 separated by radially extending prongs or teeth 38, 38 on the flanges. The two series of ports 37 in the two flanges are located on corresponding sides of the piston. 50 Each series of ports extends substantially throughout the angular or circumferential dimension of the chambers formed by and between the sliding abutments. When two abutments are employed, said ports extend 55 through substantially one-half of the circumference of the flanges, that is to say, from a point near the line along which the piston has bearing against the cylinder wall, to a point diametrically opposite said bearing line. The several ports 37 are made of equal radial length, and of the same length as the admission port 29 except in the part of the flange at which the distance between the piston and periphery of the flange is less 60 than the radial dimension of the stationary 65

port 29, so that in the narrower part of the flange, the ports 37 are cut through the full width of the flange. The unnotched or solid portion 39 of each piston flange constitutes a valve closure which covers the admission 70 port 29 at one side of the cylinder while the notched portion of said flange is passing over the admission port 29 at the other side of the cylinder.

During the rotation of the piston and its 75 flanges the ports 37 in both flanges are carried successively over two of the ports 29 of the cylinder heads and when any one of the ports 37 in the valve flange is opposite one of the ports 29 air passes freely into the interior of the cylinder. By reason of the close spacing of the ports 37, practically continuous inlet port openings are provided at the ends of the cylinder, on one side of the piston, during the time said ports 37 are 80 passing the stationary ports 29, the inlet of air being only interrupted by the passage of the solid portion or teeth 38 of said flanges which latter are preferably made narrower than the stationary ports 29. The said 85 ports 37 of the valve flanges of the piston are made narrower than the width of the end bearing faces of the abutments 22, so that during the time a given port is passing the end bearing face of either abutment, the 90 said bearing face covers or bridges the port. The result of making the end bearing faces of said abutments 22 of a width greater than the width of one of the ports 37, is to prevent 95 the back passage of air from the chamber 100 compartment of the cylinder into which air is being admitted through one pair of the admission ports 29 to the other chamber or compartment, the admission ports 29 of which latter are at this time covered by the 105 solid parts 39 of the piston valve flanges.

A device is provided which acts on the outer edges of the sliding abutments to hold the same yieldingly against the cylinder, while permitting said abutments to slide inwardly and outwardly in unison, one of the abutments being arranged to slide outwardly while the other abutment slides inwardly. The means herein shown for this purpose consists of a reciprocating frame 110 having parts which are connected with the abutments at the opposite sides of the cylinder and connecting parts which extend transversely across the cylinder from one side of the compressor to the other. As 115 herein shown said frame comprises vertical bars 42, 42 arranged in pairs at each side of the pump, one at each end thereof, and horizontal connecting rods 43, 43 extending transversely between and connecting the 120 upper and lower ends of said bars arranged above and below the cylinder. The said bars 42, 42 press at their longitudinal central portions against the ends of the abutments 26. As herein shown, the said bars 125 130

carry near their longitudinal centers bearing plates 45 which are attached to the bars by bolts 46 or otherwise and are provided with horizontal slots or grooves which receive the 5 outer edges of the abutments. The connection between the cross rods 43 and the vertical bars 42 of said frame is a resilient connection whereby the abutments are pressed yieldingly against the piston. As herein 10 shown said yielding connection is afforded by coiled springs 47, 47 which surround said rods 43 at one side of the frame and are interposed between the outer faces of the adjacent bars 42 and nuts 48 which are screw-threaded to the ends of said rods. The other ends of the rods are provided with nuts 49 which have screw-threaded engagement with the rods and constitute shoulders which confine the adjacent bars 42 on the 20 rods. With this construction it will be noted that in the outward horizontal movement of one of the abutments the reciprocating frame described acts to move the other horizontal abutment inwardly. Said frame, 25 therefore, causes the inner edges of both abutments to follow the eccentrically moving curved surface of the piston and yieldingly holds both abutments against the pistons.

30 In order to provide against leakage of air past the peripheries of the piston valve flanges 35, the said flanges are fitted into annular grooves or rabbets 50 formed at the ends of the cylinder wall between the cylinder wall of the cylinder and the end walls thereof; said flanges extending beyond the inner cylindric surface of the cylinder, as clearly shown in Figs. 1 and 6.

In the operation of the pump or 40 pressor described air is admitted to one side of the piston between one of the abutments and the line of contact of the piston with the cylinder, practically continuously during the time the ports 37 of the piston valve flange 45 are moving past one pair of the stationary admission ports 29; the duration of the inlet period being substantially equal to the period in which the piston makes a half rotation. During the time air is thus admitted to one side of the piston, the air previously admitted to the other side of the piston is being compressed between the abutment located adjacent to the closed admission ports 29 and the side of the piston which 50 is in contact with the cylinder, and the air thus compressed is forced out of the cylinder through the valved exit port 30 adjacent to said latter abutment, into a suitable receiver with which the pipe 32 connects. After the 60 last or trailing ports 37 of the piston valve flanges have passed the admission ports 29, through which air has been admitted to one side of the piston, the solid portions 39, 39 of the pistons cover said latter ports, and in 65 the continued rotation of the piston, the air

admitted to this side of the piston is compressed and forced out of the exhaust port 30. Immediately after the trailing ports of the series of ports 37 have passed the admission ports 29 at one side of the cylinder, 70 through which air has just been admitted to the cylinder, the leading ports of said series are brought into alinement with the admission ports 29 at the other side of the cylinder, and during the continued rotation of the piston 75 and while the air is being compressed on the other side of the piston, air is admitted to that side of the cylinder through which communication has been opened through the admission ports 29 and the series of ports 37. 80 The rotative piston having end flanges provided each with a series of ports, which ports are severally narrower circumferentially than the end bearing faces of the sliding abutments in contact with said flanges, affords a 85 simple compact and efficient valve device for admitting air to the cylinder, arranged so that air may be admitted to the cylinder during practically the entire inlet movement of the piston. This construction avoids the 90 use of complicated movable valve parts and actuating means therefor, such as have heretofore been used for this purpose. The essential features of the valve mechanism are formed on rigid parts of the structure, and, 95 being made of few parts, gives slight liability to derangement of the parts.

The cylinder wall and piston are water cooled and we have herein shown a simple and efficient means for leading the cooling water or fluid to the parts to be thus cooled, as will now be described. The two parts or shells of the cylinder are provided with water spaces 55 each of which is provided at one point with an inlet opening connected with an inlet pipe 56 and at another point with an outlet opening communicating with an outlet pipe 57. The piston is made hollow, comprising a sleeve portion 59 and a hollow portion divided into a plurality of spaces 60 by radial partitions 61, 61. The features of construction employed for admitting a cooling liquid to the moving piston through the stationary cylinder are made and arranged as follows: The cooling liquid is admitted to the piston through one of the heads of the cylinder through the medium of an inlet pipe 58 at a point below the engine shaft and is discharged therefrom through the other head of the cylinder and an outlet pipe 62 located 100 above said shaft. The inlet pipe communicates through an opening in the cylinder head with an annular groove 63 on the inner face of the adjacent cylinder head which is located in alinement with a corresponding annular groove 64 in the outer face of the piston and its valve-flange, the two oppositely located grooves constituting an annular or circular passage between the closely fitting stationary head and movable piston. 105 110 115 120 125 130

- The said cylinder head is also provided on its inner face with a smaller concentric annular groove 65 which is arranged opposite a like groove 66 formed in the outer face or end of the piston. The two grooves 65 and 66 constitute a circular passage which communicates with the outer groove through the medium of a plurality of radial passages 68 formed in the outer end face of the piston.
- 10 A like arrangement of grooves between the stationary head and the movable piston at the other end of the cylinder is provided, the outlet pipe 62 communicating with the outer annular passage. The inner or smaller passage at the inlet side of the device communicates through a short passage 70 in one end of the piston wall with one of the hollow spaces 60 at one side of the hollow piston. At the other end of the piston a like passage 20 70 connects another of the spaces 60 at the other side of the piston with the circular and radial passages which lead to the outlet pipe 62. The partitions which divide the hollow piston into a chamber of separate compartments are so arranged that the cooling water or liquid passes through the compartments of the hollow piston in a tortuous path, thus 25 distributing the cooling liquid more uniformly over the heated surfaces of the piston.
- 30 As shown in the accompanying drawings, each of the partitions 60 is provided at one end with a slot or opening, as shown at 72 in Fig. 6, to afford communication from one compartment of the hollow piston to the other. The openings or slots of the several partitions are arranged alternately at opposite ends of the cylinder, so that the cooling liquid will pass endwise through the spaces 35 between the partitions. By an arrangement 40 of the space or passage between the end of the piston and the cylinder head, such as is shown by which said passage covers or embraces a substantial portion of the areas of said parts the cooling medium circulated 45 therethrough seems to abstract the heat from the said end of the piston and the cylinder head, as well as from the cylindric wall of the hollow piston.
- We claim as our invention:
- 50 1. The combination of a cylinder provided with exit ports and in its head with admission ports, an eccentric rotary piston in said cylinder provided at its end with a flange bearing against the inner face of the cylinder head, said flange being provided with a circumferentially arranged series of ports adapted to pass over the cylinder inlet ports, and sliding abutments extending through the side wall of the cylinder and bearing at their inner 55 margins against the piston and at their ends against said flange, the end bearing surfaces of said abutments being made of a width greater than the width of the ports in said flange.
- 60 2. The combination of a cylinder provided

with exit ports and in its head with inlet ports, an eccentric, rotary piston provided at its end with a flange bearing against the inner face of the cylinder head, said flange having a circumferentially arranged series of 70 ports arranged to pass over the cylinder inlet ports, sliding abutments extending through the cylinder and bearing at their inner margins against the piston and at their ends against said flange, said abutments having 75 end bearing faces of greater width than the width of the ports in the flange, and the said ports occupying a part of the circumference of the flange substantially equal to the angular spaces between the sliding abutments. 80

3. The combination of a cylinder provided with exit ports and in its head with inlet ports, an eccentric rotary piston provided at its end with a flange bearing against the inner face of the cylinder head, said flange 85 being concentric with the cylinder and adapted to cover the inner face of the cylinder head and provided in its margin with a series of radial notches constituting inlet ports, sliding abutments extending through the cylinder 90 and bearing at their inner margins against the piston and at their ends against said flange, the end bearing face of said abutments being of greater width than the width of the said notches. 95

4. The combination of a cylinder provided with exit ports and in its head with inlet ports, an eccentric piston in the cylinder, provided at its end with a flange bearing against the inner face of the cylinder head, 100 and provided with a circumferentially extending series of ports arranged to pass over the inlet ports, and sliding abutments extending through the cylinder and bearing at their inner margins against the piston and at 105 their ends against said flange, said flange being larger in diameter than the bore of the cylinder and the latter having an annular groove to receive the margin of said flange.

5. The combination with a cylinder and a 110 rotative, eccentric piston therein provided with a flat end adapted to bear against the inner flat face of the cylinder head, said piston being hollow, of means for supplying a cooling liquid to the interior of the hollow 115 piston, comprising opposing circular grooves on the adjacent faces of the cylinder head and piston arranged to provide an annular passage between the same, said piston being provided with a passage which affords communication between said annular passage 120 and the interior of the piston.

6. The combination with a cylinder and rotative, eccentric piston therein provided with flat ends adapted to bear against the 125 inner flat faces of the cylinder head, said piston being made hollow, of means for supplying a cooling liquid to the interior of the hollow piston and discharging the same therefrom comprising opposing circular grooves in 130

the adjacent faces of the cylinder heads and piston, arranged to provide annular passages between the same, said piston being provided in its ends with passages which afford communication between said annular passages and the interior of the piston, at the ends of the same, and supply and discharge passages connected with the said annular passages.

7. The combination with a cylinder and a 10 rotative, eccentric piston therein provided with flat ends adapted to bear against the inner flat faces of the cylinder head, said piston being made hollow, of means for supplying a cooling liquid to the interior of the 15 hollow piston, comprising opposing circular grooves on the adjacent faces of the cylinder heads and piston, arranged to provide annular passages between the same, said piston being provided with passages which afford 20 communication between said annular pas-

sages and the interior of the piston, the hollow piston being provided with a series of radial partitions forming a plurality of compartments therein and said partitions being provided with openings affording communication between the compartments, the openings in the partitions being arranged out of line with each other to afford a tortuous path for the cooling liquid through the hollow piston.

25 In testimony that we claim the foregoing as our invention we affix our signatures in the presence of two witnesses, this 7th day of November A. D. 1908.

HERMAN A. POPPENHUSEN.
JOSEPH HARRINGTON.
